(57) **CLAIM**

The ornamental design for a hand exercising device, as shown and described.

DESCRIPTION

FIG. 1 is a perspective view of a hand exercising device;
FIG. 2 is a side view of a hand exercising device;
FIG. 3 is a front view of a hand exercising device;
FIG. 4 is a rear view of a hand exercising device;
FIG. 5 is a bottom view of a hand exercising device;
FIG. 6 is a top view of a hand exercising device;
FIG. 7 is a perspective view of a hand exercising device with the tension adjustment arm extended;
FIG. 8 is a side view of a hand exercising device with the tension adjustment arm extended;
FIG. 9 is a front view of a hand exercising device with the tension adjustment arm extended;
FIG. 10 is a rear view of a hand exercising device with the tension adjustment arm extended;
FIG. 11 is a bottom view of a hand exercising device with the tension adjustment arm extended; and,
FIG. 12 is a top view of a hand exercising device with the tension adjustment arm extended.
